UNITED STATES PATENT OFFICE

2,017,394

METAL CASTING

John J. Boax, McKeesport, Pa., assignor to
 National Tube Company, a corporation of New
 Jersey

Application April 16, 1934, Serial No. 720,869

1 Claim. (Cl. 22—79)

This invention relates to apparatus for casting molten metal, particularly molten steel, one of the objects being to obtain better castings. Other objects may be inferred.

5 Referring to the drawings:

Figure 1 is a sectional view showing a steel ladle, a tundish and an ingot mold, the last element being of reduced size to conserve space in the illustration.

10 Figure 2 is an enlarged top view of the nozzle in the tundish.

Figure 3 is a longitudinal cross-section of a different kind of nozzle which may be used in the tundish.

15 Figure 4 is an elevation looking in the direction of the arrows IV—IV in Figure 3.

Figure 5 is a top portion of this nozzle looking in the direction of the arrows V—V in Figure 4.

20 Figure 6 is a top view looking down in the direction of the arrows VI—VI in Figure 5.

A conventional teeming ladle 1 is arranged over a tundish 2 beneath which an ingot mold 3 is positioned. The molten metal is teemed from the ladle 1 into the tundish 2 from which it is 25 in turn teemed into the ingot mold 3.

The nozzle 4 of the tundish 2 is characterized in that it consists of a refractory body through which a plurality of parallel passages 5 extend from end to end. These passages 5 are adjacently grouped and one end of the body is shaped to provide a concave face 6 which cooperates with a stopper of sufficient size to close all of the adjacent openings to the passages 5. This stopper 30 may be of the usual type consisting of a bar 8 surrounded by a refractory 9 and having a graphite tip 10.

Among ingot defects are blow-holes formed by included gases and surface slivers caused by metal which has splashed onto the side of the mold during pouring.

The apparatus described converts the solid heavy stream coming from the teeming ladle 1 into a number of small lazy streams flowing into the ingot mold. This permits escape of some of the included gases and decreases splashing of the metal as it strikes the bottom of the mold. These advantages are particularly apparent if the casting is carried out in vacuum.

In the other illustrated arrangement, the tundish 2 is provided with a different teeming nozzle that consists of a refractory body 11 shaped for insertion in the nozzle opening of the tundish and in which a plurality of parallel passages 12 are formed. The top of this body is shaped so that the portions 13 surrounding the passages 12 extend upwardly to different heights. By this means the metal may be teemed in volumes varying according to the amount of metal in the tundish. The portions 13 should be arranged so that rising metal in the tundish 2 will flow through one after another of the passages 12.

Referring more specifically to this variable volume nozzle, the portions 13 of the refractory body 11 are arranged so that there is a central upstanding one 13a surrounding a central relatively large passage 12a. A second portion 13b concentrically surrounds this upstanding portion 13a and has a 15 sloping top edge that spirals downwardly around the same. Other passages 12b are arranged parallelly around the passage 12a and open from the top edge of the portion 13b whereby they open into the tundish at various heights. These passages 20 may be somewhat smaller than the central one.

Although a specific example of the invention is described in accordance with the patent statutes, it is not intended to limit the scope of the invention exactly thereto, except as defined by the following claim.

I claim:

A teeming nozzle for molten metal, including a refractory body shaped for insertion in the nozzle opening of a tundish and having a top constructed to provide a central upstanding portion through which a passage is formed, and a second portion that concentrically surrounds said central portion and which has a sloping top edge that spirals 35 downwardly around the same, other passages being formed through said body parallel to the first named passages so as to open into the top edge of said second portion at spaced positions, all of said passages being straight and opening through 40 the bottom of said body.

JOHN J. BOAX.
